Primary Examiner — Kimberly Barnes(74) *Attorney, Agent, or Firm* — Barnes & Thornburg LLP(57) **CLAIM**

We claim the ornamental design for a visor for a football helmet, as shown and described.

DESCRIPTION

FIG. 1 is a perspective view of a visor for a football helmet showing our new design;

FIG. 2 is a front view of the visor of FIG. 1;

FIG. 3 is a rear view of the visor of FIG. 1;

FIG. 4 is a right side view of the visor of FIG. 1;

FIG. 5 is a left side view of the visor of FIG. 1;

FIG. 6 is a top view of the visor of FIG. 1; and,

FIG. 7 is a bottom view of the visor of FIG. 1.

Those portions of the visor which are presented in the Figures with dotted lines (“- -”) show the environment of the visor and form no part of the claimed visor. The dot-dash-dot broken lines (“- — -”) in the Figures represent unclaimed boundaries of the visor. Moreover, any shading presented in the accompanying Figures is provided merely to highlight the contour of the visor and is not intended to be illustrative of the visor’s texture or gloss.
